Timothy Van Antwerp,
INVENTOR
BY Victor J. Evans

ATTORNEY

UNITED STATES PATENT OFFICE.

TIMOTHY VAN ANTWERP, OF SPARLAND, ILLINOIS.

AIR DEFLECTOR OR DISTRIBUTOR.

Application filed June 1, 1927. Serial No. 195,845.

My present invention has reference to a heat regulator for pipeless furnaces.

As is well known pipeless furnaces are provided with a register through which the heated air passes from the furnace into the room above and this register is surrounded by a grating or register that provides a return passage for the air. With this type of heaters the hot air enters approximately the center of the room or at least a place in the room directly over the furnace, and this heated air naturally rises to the ceiling and circulates thereover and around the side walls before it is returned through the outer register to be again heated by the furnace. Because this type of furnace does not properly diffuse the heated air around the room the same have, to a great extent been proved unsatisfactory and it may, therefore, be considered the primary object of this invention to provide a heat regulator that includes a flat plate having a round opening and being provided on its upper face with a semi-conical air deflector and distributor that is disposed over one-half of the opening through the plate, so that the heat from the furnace passing through this member will be directed through the open mouth thereof, the plate being of a size to cover the return air inlet or register for the furnace at the part thereof opposite the heat outlet of the register, so that the heat will be directed downwardly as well as upwardly and against one side of the room, so that the heat will circulate around the entire room before it can return through the exposed part of the register, with the result that a better circulation of warm air and a better heated room is afforded.

The drawings which accompany and form part of this application illustrate a satisfactory embodiment of my improvement, and wherein:

Figure 1 is a plan view of the improvement, showing the same in applied position.

Figure 2 is an edge view thereof looking toward the open end of the deflector.

Figure 3 is a central longitudinal sectional view approximately on the line 3—3 of Figure 2.

In Figure 1 of the drawings I have illustrated the register in the room above the outlet of a pipeless furnace. The central grating of the register 1, through which the hot air passes from the furnace, is, in the usual manner, surrounded by the grating 2

through which the air is returned to the furnace.

My improvement comprises a flat plate 3 of a size to rest over and cover a part of the grating 2. The plate is formed with a round opening 4, and this opening is disposed over the hot air outlet grating 1 of the register. The plate 3, has one of its ends rounded to provide an edge which is concentric with the round opening 4 therethrough, and this rounded portion of the plate is for distinction indicated by the numeral 5 and the edges of the rounded wall are concaved toward the edges of the plate proper, as clearly disclosed by the drawings. The portion 5 may be termed a rim for the plate 3, and this rim is disposed to partly cover the grating 2. The inner edge of the rim is formed with an upwardly directed deflector 6. The deflector is of a substantially semi-frusto conical formation, the same being flared downwardly from its apex 7 to its juncture with the plate 3. The open face of the deflector is, of course, directed toward the end 8 of the plate opposite that provided with the rim 5 and the deflector has arranged thereon a handle portion 9.

With the ordinary type of pipeless furnaces the heat rises vertically through the grating 1 of the register and in order to obtain warmth therefrom a person must place himself directly over this grating. With my improvement the currents of warm air are contacted by the deflector 6 and directed outwardly through the mouth thereof and from thence the currents of such warm air will be directed around the entire surface of the room before returning to the furnace through the grating 2. In this manner it will be seen that the heat currents are directed both upwardly and downwardly to one side of the room and from thence up to the ceiling and then across and down on the opposite side so that occupants of the room even when seated opposite the outlet mouth of the director member 6 will be sufficiently warmed by the continuous circulation of the air.

It is believed the simplicity of the construction and the advantages thereof will be understood and appreciated by those skilled in the art to which such invention relates without further detailed description.

Having described the invention, I claim:

1. A deflector for the heat currents from the warm air outlet grate in the center of

the register for a pipeless furnace, including a member which is disposed to close the major portion of the outer cold air grating of the register and which member has a central opening therethrough disposed opposite the inner warm air grating of the register and a hollow semi-conical directing member covering one-half of the opening and having its mouth directed to the edge of the member that is disposed entirely over the outer grating.

2. In a device for the purpose set forth, a flat plate having a rounded opening there-

through and having a round rim arranged outward of the opening and the edges of the rim concaved to the juncture of the rim with the edges of the plate, a deflector having its edge attached to the rim and covering one-half of the opening in the plate, said deflector comprising a member which is flared from its central portion downwardly to its juncture with the plate and a handle on said deflector.

In testimony whereof I affix my signature.

TIMOTHY VAN ANTWERP.
